UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

BUTTON.

1,378,074.

Specification of Letters Patent. Patented May 17, 1921.

Application filed February 16, 1920. Serial No. 358,883.

To all whom it may concern:

Be it known that I, FRANKLIN R. WHITE, a citizen of the United States, and a resident of Waterbury, in the county of New

5 Haven and State of Connecticut, have made and invented certain new and useful Improvements in Buttons, of which the following is a specification.

10 My invention relates to buttons, and particularly to that class, which are designed for attachment to cloth or other material by automatic button attaching machines, a fastener being forcibly driven through the cloth or material and upset within and accordingly securely anchored to the body of the button.

15 Heretofore it has been customary to form buttons of this class, entirely of metal, the surface of the body of the button being plated or otherwise finished so as to harmonize with the cloth to which the button is secured, and to resist the corroding influence of the atmosphere. It has been found, however, that in time the external finish upon the surface of the metallic button will wear away and allow the base metal to rust and corrode. Further the use of metal renders the button heavy, particularly in the larger sizes of buttons, also the increasing 20 cost of manufacture of metallic buttons has rendered it desirable to form the body of the button of other and less expensive material.

25 It is accordingly an object of my invention to provide a button, which is composed of metallic and non-metallic parts, so designed and arranged that a metallic fastener may be used and may be forcibly driven into the anchor of the button and upset or headed 30 therein, so as to be permanently secured thereto.

35 A further object is to provide a button suitable for attachment by an automatic button attaching machine, wherein the die or anvil, which serves merely to hold the anchor of the button against displacement during the attachment of the fastener and against shifting after the securement of the fastener, is formed of a hard non-metallic 40 substance, which may be produced in large quantities and more economically than anvils formed of metal all parts being so designed and arranged that the non-metallic parts of

the button will be protected against undue wear, abrasion and being of uniform color 55 throughout will present a pleasing and neat appearance.

With the foregoing and other objects in view, which will appear as the description proceeds, my invention resides in the combination and arrangement of parts and in the details of construction herewith described and claimed, wherein changes may be made within the scope of what is claimed without departing from the spirit of my invention.

The preferred embodiment of my invention is disclosed in the accompanying drawings, wherein;

Figure 1 is a view in vertical longitudinal 70 section of a button embodying the characteristic features of my invention.

Fig. 2 is a similar view, showing the fastener after being securely anchored to the button.

Fig. 3 is a detail view in perspective of the metallic anchor, and;

Fig. 4 is a top plan view of my improved button, parts thereof being broken away and illustrated in section.

80 Referring specifically to the several views wherein similar reference numerals designate corresponding parts throughout, the fastener A is formed with the securing prong 10, which is adapted to pierce the cloth or 85 other material B and become securely attached to the body of the button C.

90 In order to prevent the body of the button from changing in appearance, although subjected to wear and the corroding influence of water, I prefer to form the head C of the button of a hard non-metallic and substantially chemically inert material, such as fiber, which by suitable treatment may be pressed, molded, or in other ways shaped to the desired configuration. The head of the button is formed with the body 11, face 12, and flaring hub 13. The hub is preferably formed with the conical shaped opening 14, which terminates in the anchor receiving 100 receptacle 15. The face 12, is formed with an upstanding flange 16, between which is located the die or anvil 17.

105 A metallic anchor 18 is located within the receptacle 15, and has its lower extremity projecting into the conical opening 14 of the

hub. The upper extremity of the anchor is provided with the plain top surface 19, which contacts with and rests against the lower surface of the anvil 17. A metallic 5 top plate 20 extends across the flange 16, of the button body and securely holds the anvil and anchor in place. The anvil is formed of a material similar to the body and is sufficiently hard so as to transmit the force 10 from the plunger of the button attaching machine to the anchor 18, and holds the latter securely in place during the time the fastener is being upset within and secured to the anchor 18.

15 The body and anvil are formed of non-metallic material, which may be pressed, molded, and otherwise formed to shape, and incorporates in the button a certain resiliency not present when the button is formed 20 entirely of metal. Further the parts may be more economically produced than a similar button formed entirely of metal, while the uniform coloring of the body of the button prevents the appearance from changing even 25 though the surface of the button be worn away, or in any wise scarred or marred.

Having thus described my invention, what I claim is:—

1. A button of the class described comprising a body portion formed of a hard 30 non-metallic material, a metallic anchor located therein, a non-metallic and slightly resilient anvil lying above and contacting with said anchor, and a metallic cap engaging said body portion and holding said anchor and anvil in place. 35

2. A button of the class described, comprising a body portion formed of a hard non-metallic material, of uniform color throughout, a metallic anchor located therein, a non-metallic and slightly resilient anvil, contacting with said anchor, and a metallic cap, engaging said body portion, and holding said anvil in place. 40

Signed at Waterbury, in the county of 45 New Haven, and State of Connecticut, this 2nd day of Feb., A. D. 1920.

FRANKLIN R. WHITE.
